BATTERY-POST CONNECTER

Thomas J. Mayes, Ironton, Mo.

Application May 29, 1937, Serial No. 145,601

1 Claim. (Cl. 173—259)

This invention appertains to new and useful improvements in battery post connectors, and more particularly to a connector in the form of a clamp which can be applied and removed from a battery post.

The principal object of the present invention is to provide a battery post clamp of the character described in which a lubricant is contained to prevent corrosion of the battery post with the connector.

Another important object of the invention is to provide a connector of the character stated which can be readily applied and removed and which can be readily disassembled whenever desired.

These and various other important objects and advantages of the invention will become apparent to the reader of the following specification.

In the drawings:

20 Figure 1 represents a longitudinal sectional view through the connector.

Figure 2 represents a top plan view of the connector.

Figure 3 is a horizontal sectional view through the device.

Figure 4 is a side elevational view.

Figure 5 is a sectional view on line 5—5 of Figure 3.

Figure 6 is a sectional view on line 6—6 of Figure 2.

Referring to the drawings wherein like numerals designate like parts, it can be seen that numeral 5 represents a battery post receiving loop which has a tapered opening therethrough which will permit a cutting engagement of the loop into the battery post.

Numerical 7 represents a cylindrical shaped grease cup which has one end portion flattened at 8 for partly receiving the loop 5 and this flattened portion 8 is provided with an arcuate cut-out portion 9 in its top and bottom sides. The shank 10 of the loop 5 extends through the cup 7 and also through the spacer 11 which is preferably of "Bakelite", or some other non-metallic material. The spacer 11 has a reduced tapered extension 12 adapted to fit into the enlarged end of the cup 7 and this spacer 11 has a pocket 13, which with the pocket 14 in the cup 7 serves to hold a quantity of grease or other lubricant 50 which is inserted into the pockets by way of the check valve fitting 15.

The free end portion of the shank 10 is provided with threads 16 on which is feedable the nut 17. Between the nut 17 and the spacer 11 is the washer 18, and obviously by tightening the nut 17 against the washer 18 and the washer 18 in turn against the spacer 11, the spacer 11 can be

brought into compact relation with the cup 7 for forming a grease container. Furthermore, in this manner, the shank 10 is fed inwardly and outwardly of this structure so that the battery post (not shown) is clamped between the outer 5 portion of the loop 5 and the arcuate portion 9 of the cup 7.

A socket member 19 has a threaded recess for receiving the free end of the shank 10 and this has a pocket 20 therein into which the usual battery cable can be sweat soldered or otherwise secured in place.

Obviously, the grease will prevent corrosion of the post with the clamp and the fact that the spacer 11 is non-metallic, will prevent corrosion between these parts so that these parts can be readily disassembled whenever desired.

While the foregoing specification sets forth the invention in specific terms, it is to be understood that numerous changes in the shape, size, 20 and materials may be resorted to without departing from the spirit and scope of the invention as claimed hereinafter.

Having thus described the invention, what is claimed as new is:

A battery post connector of the class described comprising a cable attaching and post embracing unit, said unit having loop portion at one end to encircle the battery post, a shank of general rectangular cross sectional form integrated 30 with said loop and extending from one side thereof, said shank including a cylindrical screw-threaded portion having cable attaching means, a separate clamping jaw unit, the latter unit being cylindrical at one end and of rectangular 35 tubular form at the opposite end, the last named end slidably embracing said rectangular shank portion and coordinating with the loop slidably to permit it to clamp against said post, the complementary portions of said hollow jaw unit surrounding the shank in spaced relation to provide a grease accommodation and retaining chamber, an adjusting and binding nut on the threaded portion of said shank, and a non-metallic spacer member interposed between the nut 40 and said slidably jaw unit, said spacer surrounding the shank in grease-tight contact at one end, the opposite end portion surrounding the shank in spaced relation to communicate with said grease chamber, the last named end 45 portion of the spacer having a reduced extremity fitting in telescopic connection with the adjacent end portion of said jaw unit to provide a substantially grease-tight joint between the spacer member and said jaw unit.
